UNITED STATES PATENT OFFICE.

LOUIS AUGUSTIN ROSE, OF PARIS, FRANCE, ASSIGNOR TO L. STRAUS & SONS,
OF NEW YORK, N. Y.

DESIGN FOR THE ORNAMENTATION OF GLASS VESSELS.

SPECIFICATION forming part of Design No. 21,727, dated July 19, 1892.

Application filed June 24, 1892. Serial No. 437,914. Term of patent 14 years.

To all whom it may concern:

Be it known that I, LOUIS AUGUSTIN ROSE, of Paris, in the Republic of France, have invented new and useful Improvements in Designs for the Ornamentation of Glass Vessels; and I do hereby declare the following to be a full, clear, and exact description of said invention.

The accompanying drawing, forming part of this specification, represents the ornamentation as applied to a goblet, and said drawing will be sufficient to enable others to apply the design to various glass vessels.

The leading features of my design consist of a scroll band composed of a line of finer scrollwork and a series of sprays of leaves extending above and below said scroll band.

The design is a repeated one. Hence I illustrate in the drawing but one complete section of it, it being understood that the design is to be reproduced at the right and left of said section in the same form to such extent or

number as the size of the glass vessel warrants. The scroll band, having its loops at different distances from the edge of the glass vessel, is composed of a fine scroll line, the loops of which are of substantially uniform length. Above and below the scroll band are sprays of leaves, some of the sprays extending between the large loops of the band and some of the stems of the sprays appearing as crossing or crossed by the scroll band.

Having thus described and illustrated my design, what I claim, and desire to secure by Letters Patent, is—

The design for the ornamentation of glass vessels, substantially as herein shown and described.

In testimony whereof I affix my signature in presence of two subscribing witnesses.

LOUIS AUGUSTIN ROSE.
